DESIGN FOR A CORE FOR CINEMATOGRAPH FILM STOCK

John William Willis Smith, Prittlewell, England,
assignor to Ilford Limited, Ilford, Essex, Eng-
land, a British company

Application July 14, 1933, Serial No. 48,719
In Great Britain May 15, 1933

Term of patent 14 years

To all whom it may concern:

Be it known that I, JOHN WILLIAM WILLIS SMITH,
a subject of the King of England, residing at
Priory Cottage, Priory Crescent, Prittlewell,
Essex, England, have invented a new, original,
and ornamental Design for a Core for Cinemat-
ograph Film Stock, of which the following is
a specification, reference being had to the accom-
panying drawing, forming part thereof.

Figure 1 is a perspective view of a core for a

cinematograph film stock showing my new de-
sign;

Figure 2 is an end view; and

Figure 3 is a cross-section through the core
in plane through the axis thereof.

I claim:

The ornamental design for a core for cinemat-
ograph film stock as shown.

JOHN WILLIAM WILLIS SMITH.
